ELBOW DRAWBENCH

Stephen F. Kitlica, Beloit, Wis.

Application March 14, 1947, Serial No. 734,645

4 Claims. (Cl. 153—32)

1

This invention relates to improvements in elbow drawbenches, and more particularly to a machine for expeditiously producing seamless tubular elbows, return bend pipe fittings and the like.

There are available elbow drawbenches or machines adapted for the successive advancement of a plurality of seamless tubes which are forced over a fixedly mounted die mandrel and expanded or formed in accordance with the shape of said mandrel to produce seamless tubular elbows, pipe fittings and other tubular objects. In the available machines of this type the feeding of the successive tubes to the mandrel is accomplished by mechanisms which have reciprocatory movements and hence, the feeding and formation of the tubular stock is not strictly continuous for the reason that upon each rearward reciprocation of the mechanism there is a time lag. In the available machines the tubular stock is advanced to the die mandrel along a mandrel rod, and due to the fact that the stock must be periodically engaged and forced forwardly longitudinally on the rod by the advancing mechanism, the mandrel rod is ordinarily subjected to severe longitudinal strain. Efforts have been made to protect the mandrel rod against longitudinal movement or strain, and for this purpose clamps have been employed, but in the previous efforts the clamping arrangements have not been satisfactory.

With the foregoing in mind, it is a primary object of the present invention to provide an elbow drawbench wherein the tubular stock is advanced toward the die mandrel continuously, thereby increasing the speed and efficiency of the machine, with the elbow drawbench being further provided with pairs of clamp members for holding the mandrel rod against longitudinal movement or tension, which clamp members are arranged for swinging disengagement from a position at right angles to the axis of the mandrel rod to an inactive position substantially parallel to the axis of the mandrel rod, and are so manipulatable during advancement of stock on the mandrel rod notwithstanding longitudinal strain or tension imposed on the mandrel rod.

A further object of the invention is to provide a machine of the character described having means for continuously advancing along its mandrel rod a plurality of successively positioned tube sections, with such advancement taking place while the mandrel rod, which supports the die mandrel, is positively held against longitudinal movement or strain.

A further object of the invention is to provide

2

an elbow drawbench equipped with novel and effective pusher block means for advancing the tubular stock on the mandrel rod toward the die mandrel, the pusher blocks being so associated with continuous driving chains that at the termination of a stock forcing operation the forward pusher block will disengage itself from the mandrel rod and permit a subsequent pusher block to engage and forwardly propel a subsequent section or load of stock.

A further object of the invention is to provide an elbow drawbench which may be adjusted to receive tubular stock of varying sizes, which is strong and durable, which is efficient and rapid in operation, and which is well adapted to the purposes described.

With the above and other objects in view, the invention consists of the improved elbow drawbench and its parts and combinations as set forth in the claims, and all equivalents thereof.

In the accompanying drawings in which the same reference characters indicate the same parts in all of the views:

Fig. 1 is a fragmentary side view of the improved elbow drawbench, with parts broken away and in section to show structural details;

Fig. 2 is a fragmentary plan view of the machine;

Fig. 3 is an enlarged fragmentary detail sectional view taken on line 3—3 of Fig. 1;

Fig. 4 is an enlarged fragmentary side view, partly in section, of the rear end of the driving and pusher block mechanism for advancing tubular stock;

Fig. 5 is an enlarged fragmentary detail sectional view taken on line 5—5 of Fig. 1; and

Fig. 6 is a fragmentary detail sectional view taken on line 6—6 of Fig. 5.

Referring now more particularly to the drawings, and particularly to Fig. 1, it will be observed that the apparatus is supported on a suitable foundation which should include a longitudinal pit or recess to accommodate endless chains 10 and depending pusher blocks 11 on the lower extents of the chains 10. The foundation has imbedded therein a pair of interspaced longitudinally extending I-beams 12 joined by transverse beams 13. Mounted on the inner end portion of the foundation is a massive rigid support 14 which carries pairs of mounting brackets 15 for mandrel rod clamp mechanisms which will be described more fully hereinafter. On the foundation, forwardly of the support 14 is a massive rigid open frame support 16. Mounted longitudinally over the supports 14 and 16 is an elongated

mandrel rod 17 which at its forward or outer end merges into a die mandrel 18. The latter is of such size and shape as to form tubular stock forced thereover into a desired configuration for the purpose of producing seamless tubular objects such as elbows, return bend pipe fittings and the like. Obviously, the die mandrel is so connected with the die rod that it may be removed and replaced by another one in accordance with the size of the tube to be formed or the degree of bend required. As is conventional in the art, the die mandrel may be disposed in a furnace (not shown), or the tubular stock may be heated by other means to facilitate the expanding and bending thereof. That portion of the mandrel rod 17 which overlies the support 14 is formed at spaced positions with shouldered recesses 19 and 19' which are for the purpose of periodically receiving clamp blocks, later to be described, which when engaged with the mandrel rod 17, restrain the mandrel rod against longitudinal strain. This functioning of the clamp blocks occurs when sections of stock are being forced longitudinally along the mandrel rod and onto the die mandrel 18.

Within the open frame support 16, and extending forwardly thereof, is a bearing frame 20 in which there are journaled at its forward and rear end portions horizontal sprocket shafts 21 and 22. Each of the shafts 21 and 22 has fast on its outer ends sprockets 23. The pairs of sprockets on the same sides of the bearing frame 20 have trained thereabout the longitudinally extending endless chains 10, previously referred to. Pivotally associated with the endless chains 10, at variable intervals, which depend on the length of the stock sections to be advanced along the mandrel rod 17, are the previously mentioned pusher blocks 11.

The form of a pusher block 11, and the manner in which it is associated with the pair of transversely spaced chains 10, is best shown in Figs. 3 and 4. A pusher block 11 has an angularly shaped and weighted base portion 24, the upper flange of which removably and replaceably carries a plate 25 having a U-shaped recess therein which conforms to the size of the mandrel rod 17. The angular base portion 24 of the pusher block assembly 11 has laterally extending flanges, whereby, on the upper extent of the chains 10, said base portion of the pusher block assembly rides in a T-slot 26 formed in the upper face of the bearing frame 20 and is thereby caused to move in a position wherein the grooved block 25 is upright and embraces the mandrel rod 17 in contact with the rear end of a section of tubular stock 27 immediately forwardly thereof.

It will thus be seen that the pusher block assembly functions along the upper extent of the endless chains 10, when the chains are being driven, to engage the rear end of a section of stock on the mandrel rod and to push said stock forwardly along the mandrel rod toward or onto the mandrel 18. As will be seen from Fig. 3, there is substantial engagement between the grooved pusher block section 25 and the mandrel rod and substantial engagement between the pusher block section 25 and the stock section. Each pusher block assembly is pivotally carried by the intermediate portion of a transverse shaft 28 removably engaged at its extremities with links of the chains 10. As viewed in Figs. 1 and 4 of the drawings, the chains 10 are driven in a clockwise direction, and due to the angular weighted portions 24 of the pusher blocks, along the lower extent

of the chains 10, said pusher block assemblies hang in the overbalanced position best shown in Fig. 1. As a pusher block assembly rides upwardly relative to the rear sprockets 23, the undersurface of the base portion 24 of a pusher block assembly engages and rides on a curved apron 29. The apron is so arranged that at the time that the pusher block reaches the upper surface of the bearing frame 20, it is moved into the upright position of Figs. 3 and 4 and its flanged base portion then enters the T-slot 26 whereby the pusher block is maintained in the upright engaging position while being propelled, in its pushing function, along the top of the bearing frame 20. When the pusher block in question has reached the forward end of the bearing frame 20 a recess allows the rear end of the pusher block to pivot downwardly and further movement of the same is caused by the movement of the chains 10 over the forward sprockets 23. Then, the pusher block assembly in question, because of its weighted construction, pivotally moves to the position shown in Fig. 1 to disengage the section of stock it has advanced. The spacing between 25 the pusher block assemblies is such that at the same time a rearwardly disposed pusher block assembly is then in position at the rear of the upper surface of the bearing frame 20 to engage and forwardly advance another section of tubular stock 27. The endless chain drive and the association of the pusher block assemblies therewith is such that a uniform and continuous pressure is exerted against the rear ends of the stock sections 27 which are being advanced along the 35 mandrel rod 17 onto the mandrel 18.

It has previously been indicated that the outer end of the mandrel rod 17 carries the mandrel 18 and that the propelled pusher block assemblies continuously move sections of stock 27 along the mandrel rod and onto the mandrel. Obviously, such operations subject the mandrel rod to severe longitudinal strains and stresses such as might cause movement of said mandrel rod and mandrel if no means were provided to counteract this tendency. Therefore, one of the important features of the invention is the provision and functioning of two pairs of mandrel rod clamp mechanisms. With reference to Figs. 1 and 2 of the drawings, the clamp mechanisms constituting the pair at the rear end of the support 14 are designated generally by the numeral 30, while the clamp mechanisms constituting the pair at the forward end of the support 14 are designated generally by the numeral 31. In operation it is intended that a pair of clamp mechanisms be engaged with the mandrel rod and the other pair of clamp mechanisms be disengaged. The result is that one pair or the other of said clamp mechanisms, depending upon 40 whether stock is being introduced onto the inner end of the mandrel rod or whether stock is being forced forwardly toward the mandrel, is always clampingly engaging the mandrel rod, with such engagement of the clamping mechanisms being 45 within the shouldered recessed portions 19 or 19' of the mandrel rod. It should also be observed, as will appear more fully hereinafter, that the clamping mechanisms of each pair swing from a position at right angles to the axis of the mandrel rod to an open position parallel to the axis of the mandrel rod, which is highly 50 advantageous.

It was previously brought out that the inner and outer end portions of the support 14 carry 55 pairs of mounting brackets 15, and said mount-

ing brackets 15 are provided with laterally projecting extensions. Each bracket and its extension forms the means for properly mounting one of the mechanisms of a pair of clamps. As each clamp of a pair is constructed similarly to the other, except that the clamping members of a pair are oppositely disposed, and inasmuch as the clamping mechanisms of the two pairs 30 and 31 are similar, only one of the clamping mechanisms of a pair will be described in detail, and in this connection, attention is particularly invited to the showings in Figs. 5 and 6.

Rotatably mounted on the bracket 15 is a vertical shaft 32 on the upper end of which is keyed a mandrel rod clamp 33 shaped as is shown in Fig. 6. The mandrel rod clamp 33, when swung to a position at right angles to the axis of the mandrel rod 17, engages the shoulder of the shouldered recess 19' by means of a replaceable insert 34 which conforms to the shape of said recess and shoulder, and cooperates for rod clamping purposes with a companion clamp 33 and insert 34. At the lower end of the vertical shaft 32 is keyed a pinion 35. Rotative movement is imparted to the shaft 32 and clamp 33 by means of a rack 36 coacting with the pinion 35, said rack being actuated by a reciprocatable piston rod 37 which is part of an hydraulic ram assembly 38.

The mandrel rod clamp 33 is formed with an extended portion 39 opposite the rod engaging portion 34. Said extended portion 39 is adapted to coact with a horizontally reciprocatable wedge 40 when the clamping member 33 is in the position shown in Figs. 5 and 6. The wedge 40, when in the position shown in Figs. 5 and 6 engages the extended portion 39 of the clamping arm, thereby preventing swinging movement thereof while securely holding said clamping insert in engagement with the shoulder of the recessed portion 19' of the mandrel rod 17. Reciprocating motion is imparted to the wedge 40 by means of a piston rod 41 connected thereto which is part of another hydraulic ram assembly 42.

In order to disengage the clamping insert 34 from the shoulder of the recessed portion 19' of the mandrel rod 17 retracting motion is imparted to the piston rod 41 by the hydraulic ram assembly 42 so as to cause the wedge 40 to move rearwardly, out of engagement with and clear of the extended portion 39 of the clamping arm 33. With the wedge 40 in its retracted position (as shown dotted in the rear clamp mechanism 30 of Fig. 2), the clamping arm 33 may be swung from its engaged position shown in Figs. 5 and 6 to its disengaged or open position as shown by the rear clamp mechanism 30 of Fig. 2. Referring again to Fig. 6, the above-mentioned swinging movement is imparted to the clamping arm 33 by means of retractive movement of the piston rod 37 of the hydraulic ram assembly 38 acting on the rack 36 connected thereto which, coacting with the pinion 35, causes clockwise rotation of the shaft 32 and of the clamping arm 33 connected thereto. It is obvious that the simultaneous swinging movement of one of a pair of clamping arms and inserts coacting against the same shoulder of a recessed portion of the mandrel rod 17 is in a direction opposite that of the other clamping arm and insert.

To briefly summarize the sequence of operations of the improved elbow drawbench, reference is made to Fig. 2 in which the mandrel rod 17 is clampingly engaged by the clamping inserts 34

of the forward clamping assembly 31. The clamping inserts 34 of the rear clamping assembly 30 are in their open or disengaged position. A section of tubular stock of the proper length and diameter is introduced onto the mandrel rod 17 at its rear end (left end in Fig. 2) and is manually or otherwise slid forwardly until it is in a position forwardly of the recess 19 in the mandrel rod 17, as shown in dot and dash form at 43 in Fig. 1. 10 The clamping arms 33 of the assembly 30 are then closed by the action of the hydraulic rams 38 thereof, and locked in clamping engagement by the wedges 40 thereof which are moved forwardly into locking position by the hydraulic rams 42 thereof. The clamping arms 33 of the forward assembly 31 are then swung to disengaged or inoperative position in the manner hereinbefore described. With the clamping arms of the assembly 31 in inoperative position, the tubular stock is then moved forwardly to a position in which its rear end will be engaged by the grooved plate 25 of a pusher block assembly 11. This position is indicated in dot and dash form at 27 in Fig. 1. As soon as a piece of tubular stock has been moved into the last-mentioned position, the clamping arms of the assembly 31 are swung to engaging position, the clamping arms of the assembly 30 are swung to inoperative position and a second piece of tubular stock 30 is introduced onto the mandrel rod at its rear end and moved to the position 43. The pusher block assembly 11 which moves at substantially constant speed will then have pushed the first piece of tubular stock from position 27 toward the position shown in dot and dash at 45. While the pusher block assemblies are moving the first piece of tubular stock forwardly, the clamping arms of the assembly 30 are in their clamping position, and those of the assembly 31 are in their inoperative or open position. Consequently the second piece of tubular stock may be moved forwardly to a position in which it will be engaged by the pusher block assembly 11 following the one which is advancing the first piece of tubular stock along the mandrel rod 17. The clamping arms of the assembly 31 are then swung to engaging position and those of the assembly 30 are swung to inoperative position for the introduction of a third piece of tubular stock onto the mandrel rod 17. As the second piece of tubular stock is moved forwardly from position 27 it will engage the rear end of the first piece of stock and force the latter onto the die mandrel 18 whereon it will be formed to the desired configuration.

It will be noted that the operation as above outlined is continuous. At all times the clamping members of either assembly 30 or 31 are clampingly engaged with the mandrel rod, while likewise at all times, successive pieces of tubular stock are being forced over the die mandrel 18. It will be understood that one of the sprocket shafts 21 or 22 may be extended to a source of power (not shown) whereby the sprockets and endless chains are driven as desired. The hydraulic rams or jacks used for the operation of the wedges and clamping mechanisms may be connected with sources of fluid under pressure (not shown) as is conventional in devices of this type, and may be either manually or automatically controlled. It is also obvious that the mandrel rod 17 is subject to replacement according to the size of tubing to be operated on and depending upon the diameter of the mandrel rod

utilized the clamping mechanism inserts 34 are subject to replacement.

The advantage of the swinging clamping arms 33 of the improved drawbench over sliding clamping blocks of prior art machines must be emphasized. The difficulty experienced in prior machines, of sliding the clamping blocks into and out of engagement with the mandrel rod in a path at right angles to the axis of the mandrel rod, is not encountered in the present improvements. This is true because the clamping arms of the present invention, when swinging from engaged to inoperative position, move away from the shoulder with which they were engaged, in the same direction that the mandrel rod is being forced by the action of the pusher blocks in pushing the tubular stock toward and onto the die mandrel. There is no appreciable friction involved in this disengagement because there is no sliding contact between the clamping inserts and the shoulder of the mandrel rods against which it acts when clamping engaged. Similarly, there is no appreciable friction created in the operation of engaging the clamping inserts of the improved drawbench with the shoulder of the mandrel rod against which they act. It is evident that the present mechanism eliminates much wear on both the mandrel rod and on the clamping inserts. The improved mechanism additionally provides an efficient, positive and speedy means for interchange of clamping engagement by the two clamping mechanisms with separated portions of the mandrel rod, whereby tubular stock may be continuously fed onto the mandrel rod, while at the same time tubular stock is being continuously formed to the desired configuration on the die mandrel.

The improved elbow drawbench is furthermore of simple and novel construction, operates efficiently and expeditiously, and is well adapted for the purposes set forth.

What is claimed as the invention is:

1. Clamping mechanism for an elbow drawbench which includes a mandrel formed with spaced-apart shouldered recesses, comprising pairs of longitudinally spaced, oscillatable clamp members selectively embraceable with the recessed portions of said mandrel rod, means for swinging said clamp members into and out of said mandrel rod recesses, and additional means for releasably forcing said clamp members into contact with the shoulders of said recesses, the swinging movement of said clamp members being in a plane which includes the axis of the mandrel rod, and the clamp members when engaged exerting a force on the mandrel rod and longitudinally thereof to counteract longitudinal strain to which the mandrel rod is subjected during the drawbench operation.

2. Clamping mechanism for an elbow drawbench which includes a mandrel formed with spaced-apart shouldered recesses, comprising pairs of longitudinally spaced, oscillatable clamp members selectively engageable with the recessed portions of said mandrel rod, fluid pressure means

for swinging said clamp members into and out of said mandrel rod recesses, wedges movable into and out of contact with said clamp members for releasably forcing said clamp members into contact with the shoulders of said recesses, the swinging movement of said clamp members being in a plane which includes the axis of the mandrel rod, and fluid pressure means for moving said wedges.

3. Clamping mechanism for an elbow drawbench which includes a mandrel adapted to have tubes forcefully advanced along the forward end formed toward its rear end with spaced apart shouldered recesses, comprising pairs of longitudinally spaced oscillatable clamp members selectively embracable with the recessed portions of said mandrel rod, means for swinging said clamp members into and out of said mandrel rod recesses, and auxiliary means movable into and out of contact with said clamp members for releasably forcing said clamp members into contact with the shoulders of said recesses, the swinging movement of said clamp members being in a plane which includes the axis of the mandrel rod and in the direction of advance movement of tubes on the mandrel to counteract the longitudinal strain to which the mandrel is subjected by the advance movement of the tubes thereon.

4. Conveyor mechanism for an elbow drawbench which includes a mandrel rod adapted to receive tubes for advancement, comprising an endless conveyor having an operating run continuously moving in the same direction along a forward extent of the mandrel rod, weighted pusher blocks pivotally, spacedly carried by said conveyor, said pusher blocks being formed to embrace the mandrel rod when on the operating run of the conveyor and to engage the rear ends of tubes on the mandrel rod to advance the same, and means at the starting end of the operating run of the conveyor for swinging the pusher blocks into embracing relation with the mandrel rod, the weighted formation of the pusher blocks and pivotal mounting of the same causing said blocks to swing free of the mandrel rod at the advanced end of the operating run of the conveyor.
